[57] CLAIM

The ornamental design for a telephone, substantially as shown and described.

DESCRIPTION

FIG. 1 is a top plan view of a telephone showing my new design;

FIG. 2 is a side view of my new design;

FIG. 3 is a perspective view of my design, taken from the front, and to one side, and showing the telephone handset in a displaced position;

FIG. 4 is a second side view of my new design; and

FIG. 5 is a rear view of my new design.

FIG. 1

FIG. 2

FIG. 3
